UNITED STATES PATENT OFFICE.

GEORGE W. WATROUS, OF NORWICH, CONNECTICUT.

GRINDING-MACHINE.

SPECIFICATION forming part of Letters Patent No. 453,297, dated June 2, 1891.

Application filed February 16, 1891. Serial No. 381,652. (No model.

To all whom it may concern:

Be it known that I, GEORGE W. WATROUS, a citizen of the United States, residing at Norwich, in the county of New London and State of Connecticut, have made certain new and useful Improvements in Grinding-Machines, which improvements are fully set forth and described in the following specification, reference being had to the accompanying four sheets of drawings.

This invention is in machines of the class used for grinding cutlery and the like articles, and has for its object the production of a serviceable machine in which a multiple of such articles may be quickly clamped, adjusted, and ground to shape and size, the movement of the grinding-wheel being controlled by hand or by automatic mechanism, as preferred.

To more readily explain my said invention, I have provided the annexed drawings, in which—

Figure 1 is a side elevation of a grinding-machine of my simplest construction, the advance or feed movement of the grinding-wheel being controlled by hand. Fig. 2 is a side elevation of a similar machine, having automatic devices for controlling said wheel. Fig. 3 is an elevation of the machine of Fig. 2, as viewed from the left-hand end, the vertical screws 43 being broken away above the ways 40 to expose certain parts located at the rear of said screws. Fig. 4 is a top or plan view of the ways on which the grinding-wheel travels and of the feed-screw by which said wheel is controlled. Figs. 5 and 6 show, respectively, top and side views of a portion of the bed 22 with one of my improved adjustable knife-holders attached thereto. Fig. 7 is an end view of one of said knife-holders considerably enlarged, and Fig. 8 a side view of the holder of Fig. 5 removed from bed 22. Fig. 9 is a detached view of the clamp *e* employed to hold a knife during the operation of grinding, and Fig. 10 is a detached view of the binding-screw and nut used in connection with said clamp.

In the drawings, 20 denotes the bed of my grinding-machine suitably supported on legs 21, and having fixed on its upper face a block 22, on which removable clamps or holders are provided to support the knives or other work

to be ground. In Figs. 1, 2, and 3 these holders are shown as simple rectangular blocks.

Secured to bed 20 at its four corners are 55 posts 23, that support at their upper ends a frame 24, which provides bearings for a shaft 25, that constitutes the main or driving shaft of the machine. This shaft 25 may be driven from a counter-shaft, to which the fast and 60 loose pulleys 26 and 27 may be connected by a belt 28.

Hung loosely on shaft 25 is a frame 29, whose lower ends are bored to provide journal-bearings for a shaft 30, on which is loosely 65 hung a second frame 31, having journaled in its free end a shaft 32, on which the grinding-wheel 33 is secured. On the last-named shaft 32 is a small pulley 34, which is connected by a belt 35 with a larger pulley 36, secured 70 on shaft 30, which shaft bears a second pulley 37, connected by belt 38 with a large pulley 39, fixed on the driving-shaft 25. When the said driving-shaft is started, motion is communicated to shaft 30 and thence to shaft 75 32 and to the grinding-wheel 33.

Extending along each side of the machine are bars 40 on which the free ends of frame 31 rest in my simplest form of machines, as shown in Fig. 1, the ends of said bars being 80 supported between nuts 41 and 42 on vertically-threaded rods 43. The arrangement of frames 29 and 31 permits the free end of the last-named frame and the grinding-wheel to be drawn along bars 40 over the work to be 85 ground without interfering with the driving mechanism of said grinding-wheel. The vertical screw-rods 43 and nuts 41 and 42, which, as I have above stated, support the bars 40, are provided to permit said bars to be adjusted 90 vertically to compensate for the wearing away of the grinding-wheel. As said wheel is reduced in diameter-bars 40 may be correspondingly lowered by lowering nuts 41 on the screw-rods. Nuts 42 are then screwed firmly 95 down upon the ends of bars 40, and serve as check-nuts to prevent the accidental displacement of said bars.

In a machine of the construction shown in Fig. 1 frame 31 must be drawn along bars 40 100 by hand when it is desired to pass the grinding-wheel over the series of work-holders on block 22; but in the machine shown in Figs. 2 and 3 I have provided an automatic feed

mechanism by means of which the grinding-wheel may be positively and steadily moved over said work-holders. In this last-named machine one end of shaft 32 bears a wheel or roller 44, which rests and travels directly on bar 40. At the opposite end of shaft 32 the frame 31 is formed with teeth 45, cut on the perimeter of the journal-bearing of said shaft, which teeth mesh with a worm or screw-shaft 46, supported in bearings 47 on bar 40. This screw-shaft bears at one end a miter-gear 48, that meshes with a corresponding gear 49 on a shaft 50, journaled in stands 51 on rods 40, as most clearly shown in Fig. 3. Shaft 50 15 also bears a cone-pulley 52, that may be connected by belt with a corresponding pulley 53 on a shaft 54, journaled in posts 23, above the shaft 50. This upper shaft 54 has on one end a pulley 55, belted to a small pulley 56 on the 20 driving-shaft 25, and it will now be understood that when said driving-shaft is set in revolution and the grinding-wheel 33 caused to rotate motion will also be imparted to shafts 54 and 50 and to the screw-shaft 46. 25 As the latter revolves, the teeth 45 of frame 31 are caused to slowly travel along said screw, thus feeding the grinding-wheel along over the work-holders with a positive and steady movement. The arrangement of the feed-screw and teeth 45 is such that the free end of frame 31 may be readily raised and the grinding-wheel moved to any desired position over the work-holders, said teeth dropping into mesh with the screw-threads when 30 the frame 31 is lowered.

Having described my grinding-machine proper, I will proceed to explain a novel form of work-holders especially designed for supporting knives during the operation of grinding. The bed 22 is bored transversely, as at 40 57, Fig. 6, and the upper wall of said bed planed away, as at 58, thus leaving an opening equal to perhaps one-third of the circumference of hole 57. Within the circular seat 45 thus provided I place a knife-holder, whose main or body portion 59 is circular in cross-section and which fits said seat snugly, yet may be rocked to vary the inclination of its upper face. One end of the circular block 50 59 has a projecting plate 60, with an arc-shaped slot 61, through which a thumb-screw 62 passes, said screw being tapped into bed 22, and serving to clamp the circular block 59 firmly in place after the desired adjustment has been made. Hinged to the top side of block 59 at one end is a plate 63, whose upper face is preferably recessed to provide a seat for the handle and blade of a knife, the free end of said plate being drilled and 55 tapped to receive a thumb-screw 64, whose end abuts the upper face of block 59. By adjusting this thumb-screw 64 plate 63 and the knife thereon may be raised or lowered at will. To clamp the knife securely in place

I have provided a bar 65, hinged to one side 65 of plate 63 and cut away, as at 66, to fit the knife-handle. The free end of bar 65 is slotted, as at 67, Fig. 9, to receive a screw 68, whose lower end is pivoted in plate 63 and whose free threaded end bears a nut 69. 70 When it is desired to raise bar 65 to release the knife, nut 69 is unscrewed and screw 68 is swung outward, as in dotted lines, Fig. 7, when said bar may be raised, as also indicated by dotted lines in the same figure. Provision is thus made for rocking the knife to vary the bevel of the finished blade, also for raising or lowering the end of said blade to grind it thin or thick, as desired.

My grinding-machine as a whole is of simple construction, is strong and durable in its parts, and may be operated by a single attendant.

Having described my invention, I claim—

1. In combination with a bed bearing a multiple of work-holders, ways parallel with said bed supported at each end by nuts on vertical screws, as set forth, a feed-screw shaft journaled on and parallel with one of said ways, mechanism, as described, for rotating 90 said feed-screw shaft, and a grinding-wheel whose supporting-frame is formed with teeth that may engage the said feed-screw shaft, all being substantially as and for the object specified.

2. In combination with the main bed 22 of a grinding-machine and a bed fixed thereon bearing a multiple of work-holders, as set forth, ways parallel with said bed, as set forth, corner-posts secured to bed 22, supporting a frame 24, a driving-shaft 25, journaled in said frame, and a grinding-wheel-supporting frame hung on said driving-shaft, said supporting-frame being composed of two joined sections 29 and 31, the free end of section 31 being 105 supported by the described ways, all being substantially as and for the purpose specified.

3. In a grinding-machine, in combination with a bed 22, bored and slotted transversely, as set forth, a work-holder fitted to rock in 110 said bed, having at one end a lateral projection 60, with arc-shaped slot, and a binding-screw (in said slot) tapped into the bed 22, as and for the purpose specified.

4. In combination with bed 22, bored and 115 slotted, as set forth, a work-holder fitted to rock in said bed, means, as set forth, for clamping said work-holder to bed 22, a plate 63, hinged at one end to said work-holder, provided with an adjusting-screw 64 at the 120 opposite end, and a lever, substantially as described, for clamping the work in position on said plate.

GEORGE W. WATROUS.
